UNITED STATES PATENT OFFICE.

EDWARD S. DIX, OF NEW YORK, N. Y., ASSIGNOR TO THE BORATED
SPECIALTY COMPANY, OF BROOKLYN, NEW YORK, A CORPORA-
TION OF NEW YORK.

SKIRT-PROTECTING GARMENT.

No. 812,486.

Specification of Letters Patent.

Patented Feb. 13, 1908.

Application filed October 7, 1905. Serial No. 281,716.

To all whom it may concern:

Be it known that I, EDWARD S. DIX, a citizen of the United States, and a resident of the city of New York, borough of Brooklyn, county of Kings, and State of New York, (whose post-office address is No. 63 Clymer street, Brooklyn, New York,) have invented certain new and useful Improvements in Skirt-Protecting Garments, of which the following is a specification.

My invention particularly relates to that class of undergarments for women the function of which is to protect the outer clothing from soiling and contamination.

15 The periodical catamenial discharges to which women are subject are often so profuse that the usual protecting pads or bandages become thoroughly saturated, and upon any compression thereof—as, for example, when 20 the wearer assumes a sitting position—some of the fluid is expelled, soiling or staining the outer garments. This unpleasant result is particularly likely to occur where, as in traveling, there is no opportunity for frequent 25 change of the catamenial bandage proper.

The object of my invention is to provide a 30 skirt-protector which can be worn underneath the ordinary clothing in such a way as to be entirely concealed and which will effectually 35 prevent any soiling of the garments by these discharges. I accomplish this object by means of the new article of manufacture hereinafter described and claimed, reference being had to the accompanying drawings, 40 which form a part of this specification.

In the drawings, Figure 1 is a perspective view of the garment. Fig. 2 is a sectional view through the line $x-x$ of Fig. 1.

The garment consists of a shield, of any 45 suitable fabric, substantially oblong in shape. Its size and shape may of course vary somewhat; but I find that if the garment be made approximately twenty-two inches in length and sixteen inches in width it can be conveniently worn by the majority of women. The upper portion is provided with longitudinal gores 2, making the upper edge somewhat shorter than the lower one, and thus adapting it to be adjusted to the waist. This upper 50 edge terminates in a hemmed band 3, through which runs a draw-string 4 of sufficient length to pass about the waist of the

wearer. The upper edge of the garment may be fastened at the waist in any other suitable manner; but in practice I prefer the method 55 which I have described. The outer margin of the garment is left flat; but the central portion 5 is padded with medicated absorbent cotton and quilted. This padded portion 5 may of course be of any suitable size; 60 but I find it most convenient to have it bounded by lines approximately four inches from the side edges of the garment—a line about five inches from the bottom edge and a line about six inches from the upper edge. 65 These dimensions may be altered more or less to adapt the garment to women of various heights; but the proportions must be such that when the protector is fastened about the waist and at the back of the wearer 70 and hangs downward at full length the unpadded marginal portions at the top and sides will be of sufficient size so that the padded central portion will cause no alteration in the fit of the outer garments. This padded portion must be so proportioned and so placed that it will receive and absorb any excessive discharge and protect the outer garments therefrom, particularly when the wearer is sitting. Moreover, its size and situation must be such that it will make no noticeable alteration in the fit or “hang” of the outer garments. I have therefore given the proportions which I have found to be most 75 convenient.

Having described my invention, what I claim is—

1. As a new article of manufacture a skirt-protecting garment comprising a marginal unpadded portion, a centrally-located padded portion and means for attaching the garment about the waist of the wearer. 85

2. As a new article of manufacture a skirt-protecting garment comprising a marginal unpadded portion, a padded and quilted central portion of about one-fourth the area of the entire garment; a waistband with hem and draw-string, the upper portion of the garment being gored to fit about the waist. 95

EDWARD S. DIX.
